UNITED STATES PATENT OFFICE.

JAMES FLOCKHART, OF DENVER, COLORADO.

SILENCER.

1,229,434.

Specification of Letters Patent. Patented June 12, 1917.

Application filed April 14, 1916. Serial No. 91,191.

To all whom it may concern:

Be it known that I, JAMES FLOCKHART, a citizen of the United States, residing in the city and county of Denver and State of Colorado, have invented certain new and useful Improvements in Silencers; and I do declare the following to be a full, clear, and exact description of the invention, such as will enable others skilled in the art, to which it appertains to make and use the same, reference being had to the accompanying drawings, and to the characters of reference marked thereon, which form a part of this specification.

My invention relates to improvements in means for retarding the rush of water into the flush tanks of water closets, my object being to overcome or obviate the noise ordinarily incident to the flushing of a water closet, this noise being largely due to the rush of water into the flush tank from the supply pipe. This noise is very annoying in many instances, particularly where the water pressure is high. Furthermore, it is also embarrassing, and it is, therefore, highly desirable that it should be overcome as far as possible and practicable.

My improvement consists in locating in the supply pipe preferably just below the flush tank, a casing considerably larger than the pipe and containing one or more diaphragms or partitions, each composed of a plurality of members open to the passage of the liquid, the flow, however, being retarded. It is not only necessary that these diaphragms or partitions shall be open to the passage of the liquid, but it is also essential that they possess considerable strength and rigidity, otherwise the force of the water will soon destroy them. For this reason I employ perforated metal disks, the perforations being so arranged that they are staggered in the two disks with reference to one another. It is also essential that porous material as woven fabric or fine mesh material or both, be located between the two perforated disks, the mesh and woven material performing to a large extent the retarding function, while the perforated plates supply the necessary strength and rigidity to resist destruction due to the force of the water which has a pressure of from 150 pounds to 45 pounds per square inch depending on the location. 125 pounds pressure per square inch may perhaps be considered the usual or ordinary pressure to which these

diaphragms will be subjected, and assuming that the cross sectional area of the casing and of the diaphragms is four or five square inches, it will be understood that these diaphragms must be of such strength and stability as to resist several hundred pounds pressure. By staggering the perforations in the metal disks, I prevent the destruction of the woven or mesh material or both, since, if the perforations of the two metal disks were in register, the pressure of the water would form holes in the woven and mesh fabric corresponding with the perforations in the disks. However, by staggering these perforations, the woven and mesh material has a supporting backing in one disk directly opposite the perforation in the other disk, thus compelling the water after it has passed through the perforations of one disk, to move in a horizontal direction before it can pass through the corresponding perforations of the other disk.

The number of diaphragms will depend to a large extent upon the pressure. Assuming that the pressure is 150 pounds per square inch, I prefer to employ four of these composite diaphragms, the same being spaced the one from the other. If the pressure is 100 pounds I would suggest three of the diaphragms; if 80 pounds, two would undoubtedly be sufficient; while if it is as low as 45 pounds, one of these diaphragms will suffice. It will, therefore, be understood that the invention is not limited to any precise number of diaphragms, since the number may and should be varied according to the pressure, or as circumstances or conditions dictate or require.

Having briefly outlined my improved construction, I will proceed to describe the same in detail, reference being made to the accompanying drawing, in which is illustrated an embodiment thereof. In this drawing,

Fig. 1 is a central vertical section taken through the casing of my improvement, illustrating the same in connection with the supply pipe for the flush tank.

Fig. 2 is a top plan view of one of the metal disks forming a part of a diaphragm of my improved device.

Fig. 3 is a similar view of one of the mesh disks.

Fig. 4 is a view of one of the disks composed of coarse woven fabric.

Fig. 5 is a top plan view of one of the rings for spacing the diaphragms.

The same reference characters indicate the same parts in all the views.

Let the numeral 5 designate a casing whose central portion 6 is preferably cylindrical in shape and whose upper and lower extremities 7 and 8 are curved inwardly terminating in nipples open to receive the parts 9 and 10 of a water supply pipe. As shown in the drawing, the upper nipple is provided with a stuffing box construction 12 through which the pipe member passes, in order to form a water-tight joint. Furthermore, as shown, the lower nipple is interiorly threaded to coöperate with exterior threads formed on the pipe member 10 which is threaded thereinto. As disclosed, the inner extremity of the pipe member 10 protrudes a short distance into the casing 5, and is perforated as shown at 13, the perforations being inclined downwardly to cause the water which enters the casing to move downwardly in jets as indicated by the dotted lines 14 (see Fig. 2). The inner end of the pipe member 10 is equipped with a cap or closure 15, thus compelling the water which enters the casing through the pipe member 10 to pass through the downwardly inclined perforations, and thus compelling it to rise in a volume distributed over practically the entire cross sectional area of the casing. The inner extremity 16 of the pipe member 9 also extends a short distance into the casing, but as shown in the drawing, is open to allow the water to pass freely thereinto from the casing.

Between these two pipe extremities, I locate the retarding diaphragms, each of which may be designated in its entirety by the numeral 17. As these diaphragms are substantially identical, a description of one will suffice for all.

As shown in the drawing, each diaphragm is composed of four members, the same consisting of two perforated plates which for convenience will be designated 18 and 19, 18 being the uppermost plate and 19 the lowermost. It will, of course, be understood that these perforated disks or plates are substantially identical except that their perforations are staggered or out of alinement when they are assembled to form the diaphragm 17. It is, therefore, immaterial which disk, that is to say, the one designated 18 or the one designated 19, be uppermost, so long as the staggered relation between the perforations of the two disks is maintained when the latter are assembled. It is my intention to so construct and arrange the series of perforations in these two disks as to make it impossible for any two perforations in the two disks to be brought into register when the disks are assembled. This result may, of course, be accomplished by forming the perforations of one disk in circles whose radii are different from those

in the other disk. This will prevent the exact registration of any two disks when assembled regardless of the degree of movement to which they are subjected. Of course, in order to prevent any perforation of one disk from overlapping in part the perforation of another disk, there must be sufficient stock between the circles of the perforations to accomplish this purpose. In the drawing (see Fig. 2), the relative arrangement of the perforations of the two disks is illustrated, those of one disk being shown in full lines and those of the other disk in dotted lines. By showing the two sets of perforations in this figure, one set in full lines and the other set in dotted lines, a correct idea of the principle of construction may be obtained, whereby the staggered relation of the perforations in adjacent disks may be maintained when the parts of the device are assembled, regardless of the movement of either disk; and it is my intention in practice to so make these disks that it is impossible to bring any two perforations of the two disks into alinement with each other, thus requiring no special skill or attention in the assembling of the parts of the diaphragm.

Between the two perforated metal disks 18 and 19, I preferably locate a disk 20 of woven fabric and a disk 21 of metal mesh fabric, the woven fabric disk being comparatively fine. It should be understood that either the woven fabric disk or the metal mesh disk may be used alone if desired, the only desideratum being that the material arranged and located between the two perforated disks, shall be of such character as to properly perform the retarding function in coöperation with the perforated, relatively heavy metal disks which give the diaphragm strength, rigidity and stability.

In assembling the diaphragms within the casing 5, assuming that I employ a number of them, I place the outer edge of the lowermost upon a circumferential shoulder 22 formed on the casing, while the uppermost diaphragm engages a corresponding upper shoulder 23, while the diaphragms between these two shoulders are spaced by metal rings 24 which are of a size to fit closely within the cylindrical portion of the casing, within which the diaphragms are located.

To facilitate the assembling of these diaphragms and rings within the casing, I preferably form the latter of two substantially twin members whose central portions have exteriorly projecting abutting lugs 25 and 26 which are provided with registering perforations adapted to receive the shanks of bolts 27 which are secured by nuts 28. It will be understood that any suitable fastening means may be employed; also that any desired or preferable construction of the

casing 5 may be employed, either with a view to facilitate the assembling of the parts of the structure or with a view to enhance the utility of the same. It should also be 5 explained that while I prefer to make the central portion of the casing in which the diaphragms are located, cylindrical, it may have any other suitable cross sectional area.

While the use which I have more particularly in mind for this device is in connection with water closets and as a part of the supply pipe equipment, it is evident that its use is not limited to the one in question, but that it is equally applicable for use in connection 15 with other constructions where it is desirable to retard the flow of water, for the purpose of overcoming the noise incident thereto or for any other reason.

It should be explained that a relatively 20 large cross sectional area for this casing as compared with the size of the supply pipe with which it is used, is important, since, as the normal flow of water through the inlet member 10 of the supply pipe, is retarded 25 in the casing by the diaphragm construction, these diaphragms must have a relatively large cross sectional area in order to allow a sufficient volume of water to pass through the casing within a given time, to accomplish 30 the desired purpose. Hence, the cross sectional area of the casing 5 may be regulated as desired, such regulation depending to a large extent upon the size of the supply pipe with which it is employed.

It should also be explained that this device is practicable for use in connection with air or other gases as well as with liquids. In other words, it may be employed for fluids generally.

Attention is called to the fact that the spacing of the diaphragms within the casing accomplishes an important function, since the water after passing through each diaphragm has a compartment or space 45 within which it circulates freely and whereby it is evenly distributed for passage through the next diaphragm. Hence, it will be readily understood that by spacing the diaphragms much better results are obtained 50 than if all of the diaphragms where a number are used were in actual contact and thus forming a solid porous filling. The spaced

diaphragm construction while it affords the necessary retardation of the flow of liquid, at the same time permits the same to flow 55 with the necessary freedom to accomplish the desired purpose.

Having thus described my invention, what I claim is,—

1. A silencer comprising in combination 60 with a supply pipe, a casing through which the fluid is adapted to pass in an upward course, an upper and lower dome-shaped chamber in said casing, means for retarding the passage of fluid therethrough, the supply pipe projecting upwardly into the casing and provided with downwardly inclined ports for discharging the fluid downwardly against the wall of the lower dome-shaped chamber. 70

2. A silencer comprising in combination with a supply pipe, a casing, and means located therein for retarding the passage of fluid therethrough, said means including a plurality of porous diaphragms suitably 75 spaced from one another, each consisting of a pair of metal disks having perforations of equal size formed therein and an interposed strainer comprising disks of woven and metal fabric respectively, the first named 80 disks being so arranged that their perforations are staggered when the parts are assembled, whereby the fluid in passing through the casing in a given direction, is caused to move at right angles to its path 85 of travel intermediate of the diaphragms.

3. A silencer comprising in combination with a supply pipe, a casing having a cylindrical portion, means located therein for retarding the passage of fluid therethrough, 90 said means including a pair of perforated disks fitted into the cylindrical portion of the casing, the perforations of one disk being so disposed in relation to the perforations of the other as to preclude the possibility of their coming into alinement or registration during rotation. 95

In testimony whereof I affix my signature, in presence of two witnesses.

JAMES FLOCKHART.
